(57) **CLAIM**

I claim the ornamental design for a baseball brush handle, as shown and described.

DESCRIPTION

FIG. 1 is a top perspective view of a baseball brush handle embodying the new design;

FIG. 2 is a bottom perspective view of the baseball brush handle shown in FIG. 1;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

In the drawings, the broken lines are for the purpose of illustrating portions of the baseball brush handle that forms no part of the claimed design.
